UNITED STATES PATENT OFFICE.

SEYMOUR FIELD, OF QUINCY, MASSACHUSETTS, ASSIGNOR TO UNITED SHOE MACHINERY COMPANY, OF PATERSON, NEW JERSEY, A CORPORATION OF NEW JERSEY.

YELETING-MACHINE.

No. 880,376.

Specification of Letters Patent.

Patented Feb. 25, 1908.

Application filed April 12, 1906. Serial No. 311,309.

To all whom it may concern:

Be it known that I, SEYMOUR FIELD, a citizen of the United States, residing at Quincy, in the county of Norfolk and Commonwealth of Massachusetts, have invented certain Improvements in Eyeletting-Machines, of which the following description, in connection with the accompanying drawings, is a specification, like reference characters on the drawings indicating like parts in the several figures.

This invention relates to machines for setting fasteners such, for example, as eyelets or lacing hooks; and it pertains more particularly to improved means for setting fasteners of various shapes in predetermined positions on the stock. The word "position" is used herein to express the manner in which the parts or dimensions of a fastener are disposed on the stock, as distinguished from the location of the fastener as a whole relative to the area or extremities of the stock. That is to say, one "position" of an oval eyelet might be defined by saying that its greater diameter is parallel to the edge of the stock, regardless of the distance from said edge at which said eyelet is located.

It is frequently necessary to set fasteners which are non-circular, unsymmetrical or otherwise irregularly shaped, in predetermined positions on the stock and in the following description and claims the term "irregularly shaped" is to be understood as referring to fasteners such as those of this type, the dimensions of which vary in different directions measured on a plane substantially perpendicular to the setting devices. For example, it may be required to set oval eyelets in each flap of a shoe upper with their greater diameters substantially parallel, or in other angular relation, with the edge of said flap. Ordinarily machines for setting fasteners have feeding devices which deliver fasteners prearranged in the proper position to be set in the stock, *i. e.*, the feeding devices present the fasteners with their parts or dimensions disposed in that relation to the stock which they are intended finally to have when set in the stock. The setting devices of such machines have been adapted merely to set fasteners in their prearranged positions. Thus the feeding devices alone have heretofore performed the office of determining the position of the fastener on the stock. This

is well exemplified in a familiar type of machine wherein feeding devices deliver fasteners in succession into axial alinement with setting devices, and the latter set the fasteners in the stock in the position predetermined by the action of the feeding devices. Evidently, if it be desired to employ a machine having the above described characteristics, for setting fasteners in new or unusual positions on the stock, some change might be made in the feeding devices which would adapt them to deliver the fasteners in the required position. Such a change in feeding devices would at least involve considerable inconvenience and, in fact, the general organization of most machines would not permit changes in the feeding devices of sufficient scope to provide for setting fasteners in many positions which might be desired. The present invention is designed to obviate any difficulty of this sort by permitting any practicable form of feeding means to co-operate with devices for receiving fasteners from the feeding means and arranging them in a desired position which may be different from the position determined by the feeding devices.

In this connection an important feature of the invention comprises the combination of setting devices, feeding means, and means independent of the feeding means for determining the position of a fastener on the stock. A preferred embodiment of this feature of the invention consists in a machine for setting eyelets, having setting devices, a raceway for delivering eyelets to the setting devices, means for causing one of the setting devices to receive an eyelet from the raceway, and means arranged to act upon said setting device for determining the position of an eyelet in the stock.

The preferred embodiment just referred to constitutes the subject of a detailed description hereinafter set forth for purposes of illustration; but it is to be understood that this invention is not limited in the scope of its application to use in connection with this specific embodiment or in connection with machines of the same type. Certain features of the invention are applicable to machines for setting lacing hooks and other fasteners. The accompanying drawings represent portions of a machine of the type shown in United States Letters Patent, No. 603,023, granted April 26, 1898. Enough of such a

machine is shown and described herein to elucidate its operation in connection with the improvements contemplated by this invention.

5 In the drawings,—Figure 1 is a side elevation of portions of an eyeleting machine embodying this invention; Fig. 2 is an enlarged plan view of an oval eyelet such as may be set on the specific machine shown in Fig. 1; Fig. 3 is a vertical section of the eyelet shown in Fig. 2; Fig. 4 is a front elevation of the parts of the machine shown in Fig. 1; Fig. 5 is a detail rear elevation, partly in section, of the plunger for the lower setting device of 10 the machine; Fig. 6 is a detail front elevation showing the parts in proper position for the introduction of the stock; Fig. 7 is a side elevation of Fig. 6; Fig. 8 is a detail front elevation showing the punch in the act of 15 making a hole in the stock; Fig. 9 is a detail front elevation showing the upper setting device engaging the stock at the beginning of its feeding movement; Fig. 10 is a side elevation of the parts arranged as shown in Fig. 20 9; Fig. 11 is a detail front elevation showing the positions of the parts at the completion of a feeding movement of the stock. Figs. 1, 25 4 and 5 are approximately one-half size. Figs. 2 and 3 are drawn to a scale of two to 30 one. All the remaining figures are actual size.

The specific embodiment of the invention will be described in connection with the setting of oval eyelets one of which is shown 35 in Figs. 2 and 3. Each eyelet *a* has an oval head and a barrel which is oval in cross section. Preferably a supply of eyelets is contained in a hopper (not shown) from which they pass with their barrels extending 40 upwardly into an appropriately constructed raceway *b*. The raceway *b* is arranged to conduct the oval eyelets down its inclined floor with their barrels upward and their greater diameters extending along the line of 45 their travel. For this purpose it is especially convenient to utilize a raceway intended primarily for feeding circular eyelets of a diameter substantially or exactly equal to the lesser diameter of the oval eyelet. Thus 50 the same raceway may be used for both circular and oval eyelets. A raceway of the preferred type comprises a smooth floor which inclines downwardly, and a pair of guiding rails spaced apart a distance which is 55 slightly greater than the diameter of an eyelet barrel intended to lie between them, and spaced from the floor sufficiently to permit the heads of eyelets to travel between the latter and the adjacent faces of the rails. 60 The guiding rails as shown in the drawings are spaced from each other a distance slightly greater than the lesser diameter of the barrel of one of the oval eyelets *a*; and consequently as these eyelets proceed down 65 the raceway they will be maintained con-

stantly with their greater diameters disposed lengthwise of the raceway. Hence, with the specific arrangement shown in the drawings, when an eyelet reaches the feed end of the raceway *b* the greater diameter 70 of said eyelet will be positioned in a substantially perpendicular relation to the edge of the stock in a position which is determined by the action of the specific feeding devices. If then it be desired to set the eyelet in a position on the stock involving a different relation, it is convenient to rely upon some agency independent of the feeding devices which latter are not adapted to prearrange an eyelet in any position other 75 than that just described. The raceway *b* is supported upon a bracket *c* and is arranged to be reciprocated lengthwise toward and from the setting devices of the machine for the purpose of alternately delivering an eyelet thereto and then retiring to an inactive 80 position. This movement of the raceway may be effected by any practicable means, many of which are already known in the art, as, for example, by the mechanism shown in 85 the above-mentioned patent. 90

The operation of the machine shown in the accompanying drawings consists in three principal steps:—(1) punching a hole in the stock; (2) feeding the punched hole into 95 position for the reception of an eyelet; and (3) inserting an eyelet in said hole and clenching its barrel upon the stock. The instrumentalities for performing these several steps comprise a punch *d*, an upper set *e* and a lower set *f*. During the operation of the machine the stock is supported upon a table *g* and is held against the table under certain conditions by a presser foot *h*. The punch *d* is carried adjustably in an arm *i* 100 which is arranged to be rocked for depressing the punch against the stock. Also the punch-carrying arm *i* is arranged to be reciprocated laterally; thus, from the position shown in Fig. 4, the arm is movable in the 105 direction of an arrow 20. The punch *d* cooperates with an anvil *j*, preferably of soft metal, which is stationary during the operation of punching the hole in the stock and which partakes of the lateral movement of 110 the punch. (See Fig. 8). The upper set *e* is movable toward and from the table *g* and is also movable laterally in consonance with like movement of the punch *d*. The upper set is adjustably mounted in a carrier *k* and 115 is maintained rigid therein by a set-screw (see Fig. 6). As will be described herein- 120 after the lower set *f* is stationary laterally, its axis having a constant position. The set is, however, arranged to be vertically reciprocated for receiving an eyelet from the raceway and carrying it to the stock. 125

The presser foot *h* is held yieldingly against the table *g* by a spring *l* which bears at one end against a rigid part of the frame of the 130

machine (see Fig. 1) and at the other end against a collar (not shown) on the vertically movable rod *m* to the upper end of which the presser foot is secured. In a manner well known to those familiar with the art the presser foot is arranged to be elevated for releasing the stock when the latter is about to begin a feeding movement, and is again depressed for engaging the stock after said feeding movement has been completed. Furthermore, the presser foot may be elevated by a treadle or otherwise to permit the introduction of the stock beneath it, before initiating the operation of the machine.

15 The punch *d*, the upper set *e* and the presser foot *h* coöperate in the following manner. These parts occupy the positions shown in Fig. 6 when the operator is about to introduce the stock. The presser foot *h* is first elevated and the stock is placed upon the table *g* with its edge against an adjustable edge gage *n* (see Fig. 7) and then the presser foot is permitted to descend and press the stock against the table. Thereafter the punch is moved from the position shown in Fig. 6 to the position shown in Fig. 8 to coöperate with the anvil *j* for punching a hole in the stock. From this position the punch is moved at once upwardly and to the right (as viewed in Fig. 8). Simultaneously the upper set *e* is moved to the right until it exactly registers with the hole just punched, whereupon it descends until its projecting shank *o* enters the hole as shown in Fig. 9. In this manner the stock is securely engaged, being supported from beneath by the table *g*, and having the shank *o* of the upper set closely fitting in the recently punched hole. As the shank *o* of the upper set enters the hole in the stock the presser foot is automatically elevated to release the stock and permit it to be fed. The feeding of the stock is effected by moving the upper set from the position shown in Fig. 9 to the left (as viewed in Fig. 9) until the upper and lower sets are in exact axial alinement, the shank *o* of the upper set remaining in the hole of the stock during this entire movement. Preferably the presser foot descends to reëngage the stock shortly after the feeding movement has ceased. In order to accommodate the lateral movement of the shank *o*, and the anvil *j*, the table *g* is provided with a slot similar to that shown in the aforementioned patent. The anvil *j* projects upwardly into this slot; and the shank *o*, when the upper set is depressed, projects downwardly into the slot. Upon being elevated the lower set *f* projects upwardly through the slot to meet the upper set.

16 The operation described in the preceding paragraph may be effected by any practicable means. For example, suitable actuating means for the punch and upper set are shown in the aforementioned patent. The

arrangement and operation of the presser foot is well known to those skilled in the art. Any further illustration or description of the actuating elements for these parts would be superfluous.

70 The lower set *f* has a spring-finger *p* of the usual type and is carried on a rotatable plunger *A* which in turn is supported upon a non-rotatable plunger *q*. The plunger *A* has a shank *B* which projects into a sleeve 75 supplied by the upper end of the non-rotatable plunger *q* and said shank *B* is supported upon a ball-bearing *r*. The lateral surface of the shank *B* is grooved to receive a pin *s* which prevents relative axial movement of the rotatable plunger *A* and the non-rotatable plunger *q*. With this arrangement the plunger *A* is permitted to rotate smoothly and readily. The plungers *A* and *q* are reciprocated axially, for purposes hereinafter explained, by means of an eccentric pin *t* carried by a disk *u* which is preferably secured to the power shaft *v* of the machine. The pin *t* fits slidably in a bearing in a block *w*; and said block *v* is arranged to slide freely 90 lengthwise in a cam-path *x* provided in an enlarged portion of the non-rotatable plunger *q*. Thus, as the power shaft *v* rotates, the plunger *q*, and with it the plunger *A*, are caused to reciprocate vertically. The spring-pressed finger *p* of the lower set is normally protruded. When the set is at its lowermost limit of movement the upper extremity of the finger *p* lies directly beneath and in alinement with the endmost eyelet in the 100 raceway *b*, the latter having been projected forward to suit this purpose. This lowermost position is occupied by the lower set after the parts have been moved from the positions shown in Fig. 8 and before they 105 have reached the positions shown in Fig. 9. When at its uppermost limit of movement the lower set is in position to coöperate with the upper set for setting an eyelet in the stock (see Figs. 1 and 2).

110 As has already been stated the raceway *b* presents an oval eyelet into alinement with the lower set, in a substantially perpendicular relation to the edge of the stock as it lies against the edge gage *n*. It is assumed, for 115 purposes of explanation, that an eyelet so presented is desired to be set in the stock with its greater diameter substantially parallel to the edge of the stock. To this end the lower set *f* is arranged to receive an eyelet from the raceway and to move said eyelet, independently of the feeding means, to the position in which it is desired to be inserted in the stock. In order to accomplish this particular purpose, suggested by way of 120 illustration, it is convenient to take an eyelet from the raceway, and to rotate it about its longitudinal axis through substantially ninety degrees until its greater diameter is substantially parallel to the edge of the 125 stock.

stock. Preferably the eyelet is thus rotated about its axis through the coöperation of a cam-path C, supplied in the rotatable plunger A, and a pin D rigidly supported in the 5 frame of the machine.

The cam-path C has two vertical dwells constituting its extremities; and these dwells, for the purposes contemplated by the present discussion, are disposed at substantially 10 right angles to each other relative to the axis of the plunger A. Said two dwells are connected by an oblique cam-path. The rigid pin D is preferably threaded into that part of the frame of the machine which supplies 15 a bracket y (see Fig. 1). Obviously, when the non-rotatable plunger q is moved vertically upward, carrying the rotatable plunger A with it, the cam-path C and pin D will coöperate to rotate the plunger A through 20 substantially ninety degrees from the position it occupies when at the lowermost limit of its movement; and when the plunger q is moved downwardly, the cam-path and pin will coöperate to rotate the plunger A in 25 reverse direction to its initial position. This oscillation of the plunger A about its axis, effects the desired change in the position of the eyelet when the latter has escaped the 30 control of the raceway b, and causes said eyelet to assume the relation to the stock which it is desired to have when set.

In the operation of the machine, as already explained, the first step consists in punching a hole in the stock. When the various parts 35 are in their proper positions for the reception of the stock the lower set f is in the position shown in Fig. 6, having completed the first part of its downward travel in the direction of the arrow 21 (see Figs. 6 and 8). 40 When the punch is actuated for making a hole in the stock, the lower set is still further depressed in the direction of the arrow 21 (see Fig. 8). While the punch is being re-treated from the stock, and the upper set is 45 being moved laterally into alignment with the newly punched hole, the lower set f reaches its lowermost limit of movement. As the lower set moves downwardly during this period the raceway b is projected forwardly from the position shown in Fig. 7, 50 into the position shown in Fig. 10 wherein the last eyelet in the raceway is located in exact axial alignment with the spring-finger p of the lower set (see Fig. 10). The 55 spring-finger p is preferably oval in cross section and is of such dimensions as to fit easily within the barrel of one of the oval eyelets desired to be set on this specific machine. The lower set f is so disposed on the 60 rotatable plunger A, that the greater diameter of the oval spring-finger p will be parallel to the greater diameter of an eyelet at the feed end of the raceway, when the plunger A is at the lowermost limit of its movement and is in that angular position which is

determined by the engagement of the pin D and the upper vertical dwell of the cam-path C (see Fig. 10). As the upper set begins its descent to engage the hole in the stock just made by the punch, the plunger 70 A and the lower set f begin to move upwardly in the direction of the arrow 22 (see Fig. 10).

During the first stage of this upward movement of the lower set f, the pin D is in engagement with the upper dwell of the 75 cam-path C and consequently the spring-finger p of the lower set is maintained with its greater diameter substantially parallel with the greater diameter of the eyelet located immediately above it. These 80 relations continue as the upper set is moved for feeding the stock and until the spring-finger p, still moving upwardly, enters the barrel of the eyelet a at the feed end of the raceway and engages it securely. Just before 85 the upper set, during its feeding movement, brings the hole in the stock into axial alignment with the lower set, the oblique portion of the cam-path C engages the pin D and initiates the rotation of the plunger A and 90 the lower set f about their common axis. The relative dimensions of the spring-finger p and the interior of the barrel of the eyelet a are such that said eyelet is incapable of 95 rotating about the spring-finger. Hence, when the spring-finger has entered the barrel of the eyelet, and when the lower set has begun to rotate about its axis under the influence of the pin D, the eyelet a will also be moved angularly about its longitudinal 100 axis. When the spring-finger p has entered and firmly engaged the barrel of the eyelet a the raceway begins its retreat to inactive position and concurrently the upper set e completes its feeding movement. Thus at 105 this stage in the operation of the machine the upper and lower sets are in exact axial alignment, the shank o of the upper set projects downwardly through a hole in the stock which also registers accurately with 110 the two sets, and the spring-finger p is in intimate engagement with an eyelet. Further upward movement of the lower set f is accompanied by further retreat of the raceway and finally the eyelet a becomes 115 free from the influence of the hitherto detaining spring-stop z at the feed end of the raceway. Fig. 11 shows the parts just as 120 the raceway is about to retreat to leave the eyelet entirely free. Progressing further upward the lower vertical dwell of the cam-path C engages the pin D, the lower set f having been in the meantime rotated about its axis through substantially ninety degrees. At about the same time the upper extremity 125 of the spring-finger p strikes the lower end of the shank o of the upper set.

As shown in the accompanying drawings the cutting edge of the punch d is oval and is of proper size to punch a hole for the recep- 130

tion of the eyelet *a*. Also, the punch is so disposed relatively to the intended position of the stock on the table *g*, that the greater diameter of its oval cutting edge will lie substantially parallel to the edge of the stock; consequently, the hole is properly arranged to receive an eyelet in the desired position. The shank *o* of the upper set *e* is oval in cross section and is slightly tapered. The shank *o* is also disposed with its greater diameter substantially parallel with the edge of the stock, as is the up-setting surface encircling the base of the shank *o*. As the lower set ascends further the spring-finger *p* is held stationary by the shank *o* and is thereby depressed into the interior of the set *f*. When the lower vertical dwell of the cam-path *C* is in engagement with the pin *D* the upper and lower sets register exactly in every particular; that is to say their axes coincide and homologous diameters of their oval portions are exactly parallel. Consequently as the lower set continues to ascend the barrel of the eyelet *a*, carried by the spring-finger *p*, first encircles the tapered lower end of the shank *o*, then enters the hole in the stock, and finally the edge of the barrel strikes the upsetting surface of the upper set *e*. At this juncture the upper set is preferably moved slightly downward, while the lower set is completing its upward movement and thus the two sets coöperate to upset the barrel of the eyelet over on the stock (see Figs. 1 and 2). This completes the cycle of operations of the machine.

In order that the spring-finger *p* shall invariably be properly situated for engaging an eyelet at the feed end of the raceway it is preferred that the upper vertical dwell of the cam-path *C* be accurately formed and disposed on the rotatable plunger *A*. It is obvious that an eyelet could be set in the stock in any desired position by providing a plunger for the lower set having a suitably shaped cam-path, and by angularly adjusting the punch and upper set to suit the position intended for the eyelet. It would be within the scope of this invention to make the cam-path *C* adjustable on the rotatable plunger *A* for varying the amount of rotation of the plunger *A* and thereby permitting eyelets to be set in different positions on the stock by means of a single plunger. It is preferred, however, to provide a plurality of plunger, having cams of different designs appropriate to different positions in which it may be required to set eyelets. An indefinite number of such plungers could be employed alternatively for setting eyelets in an equal number of different positions on the stock; and, if suited to eyelets having substantially equal essential dimensions, all of said plungers could be used in conjunction with a single raceway without necessitating any change whatever in the feeding means

or in the general organization of the machine. The non-rotatable plunger *q* and the plunger *A* are readily removable, and may be replaced by a plunger having a cam of different design, by simply withdrawing the screws *E* and removing the caps of the bearings in which the plungers reciprocate.

The invention embodied in the above described specific machine is readily applicable to machines for setting fasteners of various forms and shapes in different positions on stock.

To suit certain conditions which might be met with in extended use of the invention for diverse purposes it might be necessary to make considerable alteration in the specific machine shown and described herein. The character of such changes, however, will be apparent to one skilled in the art and are, of course, to be construed as included within the proper scope of this invention as it is defined in the subjoined claims.

Having described my invention what I claim as new and desire to secure by Letters Patent of the United States is:—

1. In a machine for setting fasteners, the combination of upper and lower setting devices provided with means for determining the angular position of a fastener in the stock, means for feeding the fasteners into alignment with said setting devices, and actuating mechanism for said parts.

2. In a machine for setting fasteners, the combination of setting devices for receiving a fastener in one position, actuating means for causing said setting device to set the fastener in another position, and means actuated by the movement of said setting devices to turn the fastener about its axis from the receiving position to the setting position.

3. In a machine for setting fasteners, the combination of feeding means arranged to receive a previously formed fastener and to deliver it in alignment with the place in the stock in which it is to be inserted, means for changing the position of a fastener after it is so delivered and before the setting operation, and means for setting the fastener in the stock in said changed position.

4. In a machine for setting fasteners, the combination of setting devices; feeding means arranged to receive a previously formed fastener and to present it in alignment with the setting devices; means for changing the position of a fastener after it has been presented by the feeding means and before the setting operation; and actuating mechanism for said parts.

5. In a machine for setting fasteners, the combination of feeding means arranged to receive a previously formed elongated fastener and to deliver it in alignment with the place in the stock at which it is to be inserted with one dimension substantially perpendicular to the edge of the stock; means for

90

95

100

105

110

115

120

125

130

changing the position of a fastener so that said dimension shall have a different angular relation with the edge of the stock; and means for setting the fastener in the stock 5 in said changed position.

6. In a machine for setting fasteners, the combination of setting devices; feeding means; means independent of the feeding means for determining the position of a 10 fastener on the stock, said means being removable to be replaced by other means for determining a different position of a fastener; and actuating mechanism for said parts.

7. In a machine for setting fasteners, the 15 combination of feeding means arranged for delivering irregularly shaped fasteners; means for changing the position of fasteners so delivered; means for punching a hole appropriately shaped and positioned for the 20 reception of the fastener in its changed position; and means for setting a fastener in said hole.

8. In a machine for setting fasteners, the combination of feeding devices arranged to 25 deliver fasteners in position for insertion in the stock; means for changing the position of a fastener so delivered; means for punching in the stock a hole suitably shaped for the 30 reception of the fastener in its changed position; and means for inserting the fastener, in its changed position, into said hole and setting it therein.

9. In a machine for setting fasteners, the combination of a raceway arranged to 35 deliver fasteners in a predetermined position relative to the edge of the stock and in alignment with the place in the stock in which they are to be set; means for taking a fastener from said raceway, changing its angular position relative to the edge of the stock, and 40 setting it in its changed position in the stock.

10. In a machine for setting fasteners, the combination of a raceway arranged to 45 deliver fasteners in a predetermined position; means for taking a fastener from said raceway, changing its position, and setting it in its changed position in the stock, said means being removable to be replaced by means which set a fastener in the stock in a 50 different position.

11. In a machine for setting fasteners, the combination of a raceway arranged to 55 deliver fasteners in a predetermined position; means for taking a fastener from said raceway, changing its position, and setting it in its changed position in the stock, said means being removable to permit the substitution of means for setting a fastener in a different position in the stock.

60 12. In a machine for setting fasteners, the combination of a raceway arranged for delivering a fastener in alignment with the place in the stock at which it is to be in-

serted; setting devices arranged to receive a fastener from the raceway; and means for 65 causing the setting devices to set a fastener in the stock in a position different from that in which it is delivered by the raceway.

13. In a machine for setting fasteners, the combination of feeding means arranged to 70 receive a previously formed fastener and to deliver said fastener for the setting operation; a setting device held against lateral movement and arranged for acting upon a fastener delivered by the feeding means; means 75 for moving said setting device to change the position of the fastener; and a second setting device which co-operates with the first for setting the fastener in the stock in its changed position. 80

14. In a machine for setting fasteners, the combination of feeding means arranged for receiving and delivering a previously formed fastener; means for rotating a fastener so delivered about its longitudinal axis in order 85 to change its position; and means for setting a fastener in the stock in its changed position.

15. In a machine for setting fasteners, the combination of co-operating setting devices 90 one of which is movable about its axis; a raceway arranged to deliver fasteners to the axially movable setting device which is arranged for receiving a fastener and carrying it to the stock; and means for rotating said 95 setting device about its axis for changing the position of the fastener which it has received from the raceway.

16. In a machine for setting fasteners, the combination of co-operating setting devices 100 one of which is arranged to be axially reciprocated; actuating means for the latter; means for delivering a previously formed fastener to said setting device; and means actuated by the reciprocation of said setting 105 device for changing the position of a fastener delivered thereto.

17. In a machine for setting fasteners, the combination of co-operating setting devices; a rotatable plunger upon which one of said 110 setting devices is mounted; an axially movable plunger for carrying said rotatable plunger; means for reciprocating said axially movable plunger; means for delivering a fastener to said setting device; and means 115 operating prior to the setting operation for oscillating the rotatable plunger upon which the setting device is mounted.

In testimony whereof I have signed my name to this specification in the presence of 120 two subscribing witnesses.

SEYMOUR FIELD.

Witnesses:

ANNA CLIFFORD BRIER,
LAURENCE A. JANNEY.

It is hereby certified that in Letters Patent No. 880,376, granted February 25, 1908, upon the application of Seymour Field, of Quincy, Massachusetts, for an improvement in "Eyeleting-Machines," an error appears in the printed specification requiring correction, as follows: In line 60, page 6, the word "or" should read *for*; and that the said Letters Patent should be read with this correction therein that the same may conform to the record of the case in the Patent Office.

Signed and sealed this 24th day of March, A. D., 1908.

C. C. BILLINGS,

Acting Commissioner of Patents.
